UNITED STATES PATENT OFFICE

WALTER R. HENION, OF MINNEAPOLIS, MINNESOTA, ASSIGNOR TO BOE MANUFACTURING COMPANY, OF MINNEAPOLIS, MINNESOTA, A CORPORATION OF MINNESOTA

SPOUT CONSTRUCTION

Application filed January 27, 1930. Serial No. 423,678.

The object of my invention is to provide a spout construction consisting of a cap and a spout member, the device being adapted for use in connection with oil bottles used in service stations and being of simple, durable and comparatively inexpensive construction.

A further object is to provide a spout construction with novel means for forming a vent for releasing air from the bottle as it is 10 being filled through the spout thereof and for introducing air into the bottles as it is being emptied so that the filling and emptying operations are facilitated.

My main object is to provide in a spout 15 construction, a means for completely assembling a spout, a cap and an inner wall together without the use of solder.

Still a further object is to provide a spout 20 construction consisting of a cap adapted to be screwed or otherwise secured to a bottle or other receptacle, an inner wall in the cap for forming a vent cavity between the inner wall and the cap, portions of the inner wall and cap contacting with each other and a spout 25 extending through spout openings in the cap and the inner wall and having flanges above the cap and below the inner wall for holding the cap, the inner wall and the spout member in assembled position with respect to each 30 other.

Still a further object is to provide in a spout 35 construction having a cap formed with a top wall relative to which a spout member can be supported, an inner wall for the purpose of forming a vent cavity between the top wall of the cap and such inner wall, all or a portion of the inner wall being spaced from the top wall of the cap for forming such vent cavity.

40 Other objects are to provide means for preventing rotation of the inner wall relative to the cap and vent openings in the cap and inner wall.

45 With these and other objects in view, my invention consists in the construction, arrangement and combination of the various parts of my device, whereby the objects contemplated are attained, as hereinafter more 50 fully set forth, pointed out in my claims, and

illustrated in the accompanying drawings, in which:

Figure 1 is a perspective view of an oil bottle, as used generally in oil service stations, with one of my improved type of 55 spout constructions applied thereto.

Figure 2 is a plan view of the spout construction.

Figure 3 is a sectional view on the line 3—3 60 of Figure 2.

Figure 4 is a sectional view on the line 4—4 of Figure 3.

Figure 5 is a sectional view on the line 5—5 of Figure 2, illustrating in a laid-out formation the vent slits, baffle pockets and vent 65 cavity of the spout construction.

Figure 6 is an inverted plan view of the spout construction and

Figure 7 is a fragmentary sectional view 70 showing a special type of gasket for the device.

On the accompanying drawings I have used the reference numeral 11 to indicate an oil bottle, which is of such shape as to be readily carried by the hand 13 of a service 75 station attendant. My spout construction is indicated generally by the reference character A and consists of a cap 10, spout member 12 and inner wall 14. The cap 10 may be screw-threaded or otherwise arranged for co-acting with the top of the bottle 11 or other receptacle.

The cap 10 includes a dome-shaped top wall 16, having a central spout opening 18. The inner wall 14 has a peripheral gasket shoulder 20, adapted to contact with a gasket shoulder 22 of the cap 10 and is provided with a central spout opening 24. As shown at the left side of Figure 4, the inner wall 14 substantially fits the dome-shaped top wall 16 of the cap 10 throughout a substantial portion of its annular length. The remaining portion of its annular length is curved inwardly, as indicated at 26.

The portion 26 extends from a point referred to as 26a downwardly therefrom to the dotted line 26b in Figure 2, whereby a vent cavity 28 is formed between the top wall 16 of the cap 10 and the inner wall 14, as best shown in Figure 3 of the drawings.

The top wall 16 of the cap 10 is provided with a vent opening 30 of the slit and bulged type as best shown in Figure 5. The inner wall 14 is provided with a slit vent opening 32. The vent openings 30 and 32 are arranged to cause travel of air from the interior of the bottle 11 to the exterior thereof as indicated by the arrows 34 (see Figure 5) when filling the bottle thru its spout. When 10 the bottle 11 is being emptied (by inverting it) air rushes into the bottle as indicated by the arrows 35 for displacing the oil flowing out of it and makes possible a speedy discharge of oil from the bottle.

15 The spout 12 has an outwardly bent and an inwardly rebent flange 36 above the top wall 16 of the cap 10 and an outwardly bent flange 38 below the inner wall 14. The intermediate portion of the spout between these 20 flanges extends through the spout openings of the cap 10 and the inner wall. Thus the spout 12 is securely attached to the cap and the inner wall and holds them assembled relative to each other without the use of any 25 soldered connections, the entire assembling operation being performed for instance on a press.

30 A gasket 40 is provided for sealing against leakage of the fluid from the bottle 11 and rests against the gasket shoulder 20 of the inner wall 14. When the cap 10 is screwed onto the bottle 11, there will be some slight tendency for the cap to rotate relative to the inner wall 14 and this may be prevented, if 35 found undesirable, by upward depressions 42 in the gasket shoulder 20 of the inner wall 14, which fit into similar depressions 44 in the gasket shoulder 22 of the top wall 16 of the cap 10. No further securing means need be 40 provided to prevent rotation of the cap relative to the inner wall or vice versa.

45 In Figure 6 I have illustrated a modified form of spout construction in which the periphery of the gasket shoulder 20a is of less diameter than the inside diameter of the cap 10a. This leaves the gasket shoulder 22a of the top wall 16 of the cap 10 exposed to the gasket 40a across a space indicated by the bracket 50. Thus the gasket 40a, which may 50 be originally formed with a stepped upper surface as shown or which may be of sufficient resiliency to assume such shape upon the cap 10 being secured to the bottle 11, contacts with both the shoulder 20a and the portion 55 of the shoulder 22a for forming a seal to prevent oil from leaking out of the vent cavity 28 between the members 20a and 22a and down through the threads on the neck of the bottle 11 and then seeping down over the 60 outside surface of the bottle as is possible by the constructions shown in Figures 3 and 4. This construction forms a very effective sealing method to prevent the seepage of liquid between the unconnected outer edges of the 65 inner and upper walls 14 and 16.

From the description of my invention, it will be obvious that a spout construction is provided having the desirable features of staggered vent openings, communicating with a vent cavity in an oil cap and the parts are secured together in a simple manner without the use of solder which is a considerably more expensive process than when a flange, such as the flange 38, can be turned outwardly and pressed against the inner wall 14 for tightly securing the inner wall and the cap between such flange and the flange 36. 70 75

Some changes may be made in the construction and arrangement of the parts of my device without departing from the real spirit and purpose of my invention, and it is my intention to cover by my claims, any modified forms of structure or use of mechanical equivalents, which may be reasonably included within their scope. 80 85

I claim as my invention:

1. In a spout construction, a cap having a peripheral ledge, an inner wall in said cap and having its edge in contact with said ledge and a spout member having flanges above the cap and below the inner wall for holding the cap, inner wall and spout assembled together. 90

2. In a spout construction, a cap having a peripheral ledge, an inner wall in said cap and having its edge in contact with said ledge, said cap and inner wall having each an opening, the portions of the cap and inner wall adjacent said openings being in contact with each other, a spout secured to said cap and inner wall at such portions, a part of said inner wall being spaced from said cap to form a vent cavity and vent openings in the cap and the inner wall and communicating with said vent cavity. 95 100 105

3. In a spout construction, a cap having a gasket shoulder and a spout opening, an inner wall having a gasket shoulder contacting with the gasket shoulder of said cap and a spout opening, the portions of said cap and inner wall adjacent the openings therein contacting with each other, a spout thru said spout openings and secured to the edges of the openings, a vent cavity between said cap and said inner wall and vent openings in the 110 cap and in the inner wall. 115

4. In a spout construction, a cap having a gasket shoulder and a spout opening, an inner wall having a gasket shoulder contacting with the gasket shoulder of said cap and a spout opening, the portions of said cap and inner wall adjacent the openings therein contacting with each other and a spout thru said spout openings and secured to the edges of the openings. 120

5. In a spout construction, a cap having a gasket shoulder and a spout opening, an inner wall having a gasket shoulder contacting with the gasket shoulder of said cap and a spout opening, a spout thru said spout open- 125 130

ings and secured to the edges of the openings for thereby assembling the cap and inner wall together and coacting means on said shoulders to prevent rotation of the cap relative to the inner wall.

5 6. In a spout construction, a cap having an annular shoulder and a spout opening, an inner wall having an annular shoulder in contact with the annular shoulder of the cap and a spout opening, a spout thru said openings and secured to the edges thereof by flanges above the cap and below the inner wall for thereby assembling the cap and inner wall together, such edges being adjacent each other and clamped together by said flanges.

10 7. In a spout construction, a cap having an annular shoulder and a spout opening, an inner wall having an annular shoulder in contact with the annular shoulder of the cap and a spout opening, a spout thru said openings and secured to the edges thereof by flanges above the cap and below the inner wall for thereby assembling the cap and inner wall together, such edges being adjacent each other and clamped together by said flanges, said inner wall being spaced from said cap to form a vent cavity and oppositely arranged, staggered vent openings in said

15 30 cap and inner wall.

Des Moines, Iowa, January 7, 1930.
